UNITED STATES PATENT OFFICE.

CHARLES E. HOBSON AND JACKSON VANNOY, OF FREMONT, IOWA.

LOCK FOR DOORS AND THE LIKE.

1,299,726.

Specification of Letters Patent.

Patented Apr. 8, 1919.

Application filed July 22, 1918. Serial No. 246,170.

To all whom it may concern:

Be it known that we, CHARLES E. HOBSON and JACKSON VANNOY, citizens of the United States, residing at Fremont, in the county of 5 Mahaska, State of Iowa, have invented certain new and useful Improvements in Locks for Doors and the like; and we do hereby declare the following to be a full, clear, and exact description of the invention, such as 10 will enable others skilled in the art to which it appertains to make and use the same.

This invention is an improvement in locks and has particular reference to a fluid pressure operated lock for car doors and the like.

15 An object of the invention is to provide an improved mechanism including a lock the adjustment of which to locking position is controlled by pressure from the air brake system of a train.

20 Another object is the provision of improved means for storing a quantity of fluid pressure within a car and utilizing the same to retain the lock or locks of the car in operative position after the pressure from 25 the train pipe is cut off.

A further object is to provide means for releasing pressure from the storage tank to adjust the lock or locks to inoperative position and control said release whereby the 30 time involved in effecting the unlocking operation may be varied.

A still further object is to give warning of an attempt to open a door of a car by unauthorized persons by providing a sounding signal operated by the release of pressure from the storage tank.

35 The inventive idea involved is capable of receiving a variety of mechanical expressions one of which, for the purpose of illustrating the invention, is shown in the accompanying drawings, wherein:

Figure 1 is a fragmentary side elevation of a freight car showing the invention applied thereto.

45 Fig. 2 is a transverse section.

Fig. 3 is an enlarged longitudinal section on the line 3—3 of Fig. 1.

Fig. 4 is a top plan view of the storage tank.

50 Fig. 5 is a longitudinal section thereof.

Fig. 6 is a sectional view through the check valve for the tank.

Fig. 7 is a perspective view of one of the hasp members of the lock.

55 Fig. 8 is a detail view of a disk valve for

controlling the release of pressure from the tank.

The lock which comprises the essential feature of the invention is adapted for use on doors and windows and is shown, in the 60 accompanying drawings, as applied to the sliding doors 11 of a freight car 12.

Each lock preferably comprises a hasp 13 pivoted to the door 11, at 14, and provided at its free end with a transverse plate 15 65 having openings 16 at each end thereof adapted to receive eye bolts 17 carried by the frame of the door and adapted to receive a locking pin 18 for retaining the hasp in locking position in addition to the fluid pressure operating means, presently to be described, for performing the same function. The hasp further comprises a locking plate 19 pivotally mounted upon a pintle 20 secured transversely to the free end of the 70 hasp and said plate is adapted to extend into a slot 21 formed in the door frame and is provided with an opening 22 adjacent its free end for receiving the outer end of a locking member 23 in the form of a bolt 80 which is operated by the fluid pressure means to be described. When it is desired to dispense with the use of the fluid pressure means, the locking plate 19 may be swung to a position along side the body of the hasp 85 so that the same will not extend into the slot 21 when the hasp is adjusted to its locking position. The locking bolt 23 of each of the locks is preferably mounted to slide in one end of a cylinder 24 recessed between 90 the walls of the car adjacent the door frame and said bolt is provided upon its inner end with a piston head or plunger 25 between which and the end of the cylinder in which the bolt is mounted is interposed a coil 95 spring 26 for normally retaining the bolt in a retracted or inoperative position. The end of the cylinder opposite to that in which the bolt 23 is slidably has connected thereto one end of a pipe or flexible tube 27 for supplying fluid pressure to the cylinder from the storage tank 28 to one end of which the other end of the pipe 27 is connected.

The tank 28 is preferably mounted adjacent the top of the car and transversely 105 thereof and is supplied with fluid pressure through a pipe or tube 29 one end of which is connected to the air brake system (not shown) of a train while the other end thereof is connected to an inlet 30 carried by the 110

tank, intermediate its ends, and having a check valve 31 therein operable to close said inlet when the pressure in the tank and pipe 29 equalize or when the pressure in said pipe 5 falls below that in the tank, as when the air brake system is disconnected from the car. In this manner it will be apparent that should the air brake system become accidentally or otherwise disconnected from the 10 car the escape of pressure from the tank 28 will be prevented until released in a manner to later appear and through this medium the lock member or bolt 23 of the locks of both doors will be retained in locking or 15 operative position.

The means for releasing the pressure from the tank 28, so that each locking bolt 23 will be returned to its inoperative position when the tension of the spring 26 over- 20 comes the pressure on the other side of the piston head 25, preferably comprises an outlet 32 extending from the tank 28 intermediate its ends and having the oppositely directed branch pipes 33 extending from the 25 outer end thereof and longitudinally of the tank, said branch pipes 33 each having an opening 34 adjacent the inner end thereof for permitting the escape of pressure. In order that the escape of pressure through 30 the openings 34 may be normally prevented, each pipe 33 has mounted therein a piston 35 to which is connected one end of a rod 36 adjustable longitudinally of the pipe and having its outer end slidably 35 mounted in the side of the car and extending exteriorly thereof so that said rod may be operated from the outside of the car. When it is desired to retain the pressure within the tank 28 these rods 36 are forced 40 inwardly so that the pistons 35 will be positioned between the openings 34 and the connections of the pipes 33 with the outlet 32, and in order that the pressure from the outlet 32 will not force the pistons 35 outwardly the rods 36 are threaded into the outer ends of the pipes 33 as indicated at 45 37. It will be apparent from this description that when it is desired to release the pressure in the tank 28 either one or both of the rods 36 are adjusted outwardly so that the pistons 35 will be disposed between the openings 34 and the outer ends of the pipes 33 and thus allow the pressure to pass from the outlet 32 through said openings. 50 In order to minimize the danger of cars being opened by unauthorized persons, a sounding signal such as a whistle 38 is mounted upon a rod 39 extending from the outlet 32 and disposed in such position that the escape of pressure through the openings 34 will operate the same until the pressure in the tank is exhausted.

It is further proposed to control the release of pressure from the tank 28 in order 60 that the time consumed in effecting the ad-

justment of the locking bolt 23 to its inoperative position may be varied. To this end, use is preferably made of a disk valve 40 having an annular series of openings 42 and rotatably mounted upon the outer end 70 of the outlet 32 and held thereon by means of a key 41. The inner face of the valve 40 is in engagement with a plate 41' having openings 41" registering with the openings 34. The openings 42 are arranged in 75 an annular series and these openings through each half of the series, gradually increase in area, oppositely disposed openings of the series being preferably of the same size so that when the same are in 80 registration with the opposite openings 34, a like amount of pressure will escape through said openings. By this means, it will be apparent that should it be desirable to open the doors in a comparatively short 85 time, the valve 40 is rotated until the largest openings therein are in registration with the openings 34. This adjustment is made before doors are locked and the cars ready for transportation. If it is desirable that the pressure in the tank 28 escape slowly 90 so that the time consumed in opening the doors, after the adjustment of the rods 36, will be prolonged the valve 40 is adjusted so that smaller oppositely disposed 95 openings are in registration with said openings 34.

What is claimed is:—

1. In a fluid pressure controlled lock for doors and the like, the combination of a 100 lock including a pressure controlled locking member, a storage tank from which pressure is supplied to adjust said locking member to operative position, means for releasing the pressure from said tank whereby 105 said locking member will return to its inoperative position, and means for controlling the release of said pressure from the tank to regulate the time required for the locking member to move to inoperative position.

2. In a fluid pressure controlled lock for doors and the like, the combination of a lock including a pressure controlled locking member, a storage tank from which pressure is supplied to adjust said locking member to operative position, means for controlling the release of said pressure from the tank to regulate the time required for the locking member to move in inoperative 120 position, and a signal operated by the release of said pressure.

3. In a fluid pressure controlled lock for doors and the like, the combination with the air brake system of a train; of a storage 125 tank supplied with pressure from said system, a locking member connected to said tank and adjusted by the pressure therefrom to a locking position, means for releasing the pressure from said tank whereby said 130

locking member will return to its inoperative position, and means for controlling the release of said pressure from the tank to regulate the time required for the locking member to move to inoperative position.

4. In a fluid pressure controlled lock for doors and the like, the combination with the air brake system of a train; of a storage tank supplied with pressure from said system, a locking member connected to said tank and adjusted by the pressure therefrom to a locking position, means for releasing the pressure from said tank whereby said locking member will return to its inoperative position, means for controlling the release of said pressure from the tank to regulate the time required for the locking member to move to inoperative position, and a signal operated by the release of said pressure.

5. In a fluid pressure controlled lock for doors and the like, the combination with the air brake system of a train; of a storage tank supplied with pressure from said system, a locking member connected to said tank and adjusted by the pressure therefrom to a locking position, means for retaining the pressure within said tank whereby the locking member will remain in locking position after the air brake system has been disconnected from the tank, means for releasing the pressure from said tank whereby said locking member will return to its inoperative position, and means for controlling the release of said pressure from the tank to regulate the time required for the locking member to move to inoperative position.

6. In a fluid pressure controlled lock for doors and the like, the combination of a lock including a pressure controlled locking member, a storage tank from which pressure is supplied to adjust said locking member to operative position, an outlet for said tank having apertured branch pipes extending in opposite directions therefrom and through the apertures of which the pressure in the tank is adapted to escape, and means operable from the exterior of the car normally preventing the escape of pressure through said apertures and adjustable to permit of said escape.

7. In a fluid pressure controlled lock for doors and the like, the combination of a lock including a pressure controlled locking member, a storage tank from which pressure is supplied to adjust said locking member to operative position, an outlet for said tank having apertured branch pipes extend-

ing in opposite directions therefrom and through the apertures of which the pressure in the tank is adapted to escape, means operable from the exterior of the car normally preventing the escape of pressure through said apertures and adjustable to permit of said escape, and a valve adjustable with respect to said outlet and having various sized openings therein adapted to register with the apertures in said branch pipes whereby the escape of pressure through said apertures is controlled to regulate the time required for the locking member to move to inoperative position.

8. In a fluid pressure controlled lock for doors and the like, the combination of a lock including a pressure controlled locking member, a storage tank from which pressure is supplied to adjust said locking member to operative position, an outlet for said tank having apertured branch pipes extending in opposite directions therefrom and through the apertures of which the pressure in the tank is adapted to escape, means operable from the exterior of the car normally preventing the escape of pressure through said apertures and adjustable to permit of said escape, a valve adjustable with respect to said outlet and having various sized openings therein adapted to register with the apertures in said branch pipes whereby the escape of pressure through said apertures is controlled to regulate the time required for the locking member to move to inoperative position, and a sounding signal supported by said outlet and operated by the escape of pressure through said apertures and openings.

9. In a car door construction, the combination of a hasp pivoted to the door and having a transverse plate at one end provided with openings therein, eye bolts carried by the door frame and engageable in said openings, means engaging said eye bolts for locking the door in closed position, a locking plate pivoted to the body of the hasp and adapted to extend transversely therefrom and through the frame of the door, and fluid pressure operated means engageable with said locking plate for also locking the door.

In testimony whereof, we affix our signatures in the presence of two witnesses.
